UNITED STATES PATENT OFFICE.

ROBERT T. JOHNSTON, OF SCOTCH PLAINS, NEW JERSEY, ASSIGNOR, BY MESNE ASSIGNMENTS, TO WOOD & NATHAN COMPANY, OF NEW YORK, N. Y., A CORPORATION OF NEW YORK.

COMPENSATING AND RETRIEVING MEANS FOR PRINTING-MACHINES.

1,080,978.

Specification of Letters Patent.

Patented Dec. 9, 1913.

Application filed February 10, 1908. Serial No. 415,142.

To all whom it may concern:

Be it known that I, ROBERT T. JOHNSTON, a citizen of the United States, residing at Scotch Plains, in the county of Union and State of New Jersey, have invented a new and useful Compensating and Retrieving Means for Printing-Machines, of which the following is a specification.

In several types of printing machines where the printing is done from curved or cylindrical surfaces, it is desirable to vary the diameter of these surfaces and at the same time retain the contacting impression surface at a fixed diameter, as it is not desirable of course, to reduce the diameter of the impression cylinder to correspond with any reduction in diameter of the printing surface. It is obvious, however, that the circumferential speed must be the same for the two surfaces. In machines used for intaglio printing, this difficulty is seen particularly, because absolute designs are usually turned off and the surface prepared for a new design. In an application for patent on a relief and intaglio printing press filed by Henry A. Wise Wood, December 22, 1906, Serial No. 349,717, means is shown whereby in order to do this a yielding compensating arrangement is provided to drive the printing and impression surfaces uniformly when they are together for printing and to retrieve or bring the surfaces back into their original registration while the surfaces are traveling after the printing operation is completed. It will be obvious that in machines where the printing and impression cylinder make a single revolution, the retrieving has to be done in the margins, but when the printing cylinder makes one or more revolutions in addition to each printing revolution during a single revolution of the impression cylinder, the retrieving time equals the time of the idle revolution or revolutions of the printing cylinder.

The principal objects of the present invention are to provide an improved positive compensating and retrieving means and to construct the same in a practicable and efficient form so that it can be adjusted properly and easily whenever the diameter of the printing surface is varied, in order to produce the desired change of speed for compensating for the changed diameter and

in order to bring the shell back into original registration or retrieve it in a smooth manner; also to provide such a means which can be applied to various types of printing machines. This is accomplished by introducing between the printing cylinder or shell and its driving mechanism a compensating means which permits the shafts of the printing cylinder and impression cylinder to be set varying distances apart without disturbing the position of the centers of their driving mechanisms and providing means for alternately accelerating and retarding the speed of one of said cylinders to compensate and retrieve in the manner above indicated.

Reference is to be had to the accompanying drawings which show the invention as applied to a two-revolution intaglio printing press and in which,

Figure 1 is an elevation of a portion of such a press showing one form of the invention applied thereto. Fig. 2 is a plan of a portion thereof. Fig. 3 is an end elevation of the same. Fig. 4 is a diagrammatic view similar to Fig. 1 showing the parts as adjusted for compensation. Fig. 5 is a perspective view of the universal plate shown in the first two figures. Fig. 6 is a diagrammatic view showing another way in which this invention may be carried out. Fig. 7 is an end view thereof. Fig. 8 is a partially diagrammatic side view of another form of the invention, and Fig. 9 is an end view of the same.

Referring first to the first five figures, it will be seen that the invention is shown as applied to a two revolution press 10 having a driving shaft 11 on which is a driving pinion 12 meshing with an impression cylinder gear 13 which is connected with the impression cylinder 14 to operate the latter, in a well known way. The impression cylinder shaft 15 is shown as provided with the usual delivery cylinder gear 16 which operates the delivery cylinder 17. The machine is also shown as provided with other usual mechanism ordinarily employed in presses of this character, including the fly 18, grippers and the like. The impression cylinder gear 13 meshes with and drives a gear 20 corresponding to the usual printing roll gear. In this form of the invention, this gear is not fixed to the printing roll shaft

but is shown as meshing with a gear 21 to which is fixed a gear 22 mounted to turn on a stud 23 supported by a link 24 supported from a bracket 25 on the frame. Thus they 5 swing about the axis of the gear 20 as a center so as to constitute, in effect, planetary gearing. A gear 26 is mounted to mesh with the gear 22 so that the motion of rotation is imparted to the gear 26 in the proper ratio 10 to drive the printing cylinder 27 at the same circumferential speed as the impression cylinder when the printing shell or surface is of the maximum diameter. The gears 20 and 26 are mounted to rotate freely on a 15 stud 28. In order to provide for permitting the printing cylinder to be adjusted toward the axis of the impression cylinder when the former is reduced in diameter, it is driven from the gear 26 by means of a universal 20 plate 30 which is provided with means whereby it may receive power from the gear 26 and transmit it to the cylinder 27 even when they are eccentrically placed and drive the cylinder uniformly. This comprises 25 projecting ribs 31 and 32 on opposite sides, preferably located substantially at right angles. One rib 31 is adapted to enter a slot 33 in the gear 26 and the other rib 32 enters a slot 34 in a hub 35 fixed on the printing 30 roll shaft 36. This universal plate allows the printing roll to be moved out of alignment with its driving gear 26 without affecting the speed and permits the necessary adjustment, which is effected by adjusting 35 screws 37 or the like, operated by nuts 38 to adjust the bearings 39, of the shaft 36. Now, in order to provide for the compensating and retrieving motions which have been described above, the shaft of the impression 40 cylinder is provided with a cam 40, which is shown as having two surfaces, 41 and 42, the first for compensating and the other for retrieving. In order that the acceleration may be uniform throughout a half rotation 45 of the impression cylinder and a complete rotation of the printing cylinder, the surface 41 is made in the form of a simple spiral. In order that the return or retrieving motion may be as smooth as possible, the 50 surface 42 is preferably developed on a crank motion. Now, in order to transmit the necessary motions to the printing roll, a cam lever 50 is employed pivoted on a stud 51 and having a roller 52. A spring 55 53 is shown for holding the roller against the surfaces of the cam 40. This cam lever is indicated in Fig. 3 as of a U-shape at the bottom so that an adjusting slot 54 with which it is provided may be extended into 60 a position concentric with the stud on which it is pivoted. In this slot is adjustably mounted a pin 55 which is fixed to the end of a link 56 and is adapted to be moved along the slot and fixed in any desired position therealong. The other end of the

link 56 is connected with the stud 23. From this construction, it will be seen that the rotation of the impression cylinder will have no effect on the link 56 when the pin 55 is adjusted in the slot to a position concentric 70 with the stud 51. This is the position which it is designed to occupy when the printing surface or shell is of maximum or standard diameter and at this time, obviously, the operation of the press is like that of an ordinary press of this character. When the printing surface or shell is reduced in diameter and adjusted up into contact with the impression cylinder, the pin 55 is accurately adjusted outwardly from the axis of 75 the stud 51 so that the complete rotation of the impression cylinder will cause the roller 52 to move outwardly in a uniform manner during the first half of the revolution and then move inwardly smoothly to bring it back to its ordinary starting position, which is at the point 58 on the gear. The effect of this motion is to swing the stud 23 and the gears 21 and 22 which are 80 carried thereby. Now, the effect of this motion of these gears will be obvious when it is considered that the gear 20 with which the gear 21 meshes is positively driven by the gear 13 at a constant rate of speed. The result is that the gear 22 will move along 90 the gear 26 and vary the speed thereof in the manner of planetary gearing. As the motion of the roll 52 is uniform during the printing revolution of the printing cylinder, the acceleration of the speed of the gear 26 95 is uniform throughout that revolution and consequently by proper proportioning and adjustment of the parts, it can be made to compensate exactly for the reduced diameter of the printing surface so as to cause the circumferential speeds of the impression cylinder and printing surface to be the same 100 throughout the printing revolution. But when the printing revolution is completed, the roll drops back toward the center during the rest of the revolution of the impression cylinder, and the next revolution of the printing cylinder, so as to bring the surface of the same into its original registration with the impression cylinder which is the 105 action that I have called "retrieving". Consequently, on the third revolution of the impression cylinder, the parts will be in their normal position and the action will 110 then be repeated. Obviously, the adjustment of the pin 55 depends on the amount of reduction of the diameter of the printing surface and if desired, the lever 50 may be provided with a scale 59 registering with a mark on the link 56 to indicate the position in which the latter is to be placed for any particular diameter of the printing roll. On account of the universal plate and its 115 connections, the driving of the printing cylinder will be accomplished in an exact and 120 125 130

uniform manner even when it is off center, as has previously been stated. It will be seen that this constitutes an adjustable device whereby the speed of the printing roll during the printing operation thereof may be uniformly varied to compensate for the change in diameter from the standard, and means whereby the parts will be returned to registering position during the non-printing motion of the printing roll.

In Figs. 6 and 7, I have shown a form of the invention in which the planetary gearing connecting the printing roll with the impression cylinder gear is of the bevel gear type. That is, the gear 20 is connected with a bevel gear 60 to turn therewith. This drives a bevel gear 61 through a bevel pinion 62. The gear 61 is shown connected with a universal plate 30 in the same manner as described above. The bevel pinion 62 may be moved back and forth by the link 56 in the same manner as above and with the same effect, means, as a hanger 63, being provided for keeping the pinion in position. It is to be observed that the compensating movement given to the printing roll is double that of the connecting link 56.

In Figs. 8 and 9 is indicated a form of the invention in which the impression and printing cylinders are driven through worm wheels 64 and 65 operated by worms 66 and 67 one of which is left-handed, and one of which is slidably mounted on a driving shaft 68 so as to be turned thereby. One of the worms as 67 is moved along the shaft by a link 70 connected with a lever 71 similar to the lever 50. The sliding worm 67 is mounted in a sliding bracket 72 between bearings 73, the bracket being connected with the cam motion preferably in the same way as above by the link 70 and lever 71. The endwise motion of this worm causes it to operate like a rack through which any additional or reverse movement can be imparted to the impression or printing cylinder. The rest of the mechanism has not been shown as it may be similar to that above described.

While I have illustrated and described certain forms of the invention in which it is applied to a two-revolution press, and while I have shown certain preferred embodiments thereof, I am aware that the same may be applied to other styles of presses and that it may be carried out in many other ways without departing from the scope of the invention as expressed in the claims. Therefore, I do not wish to be limited to the particular type of press or forms of construction described, but

What I do claim is:

1. In a printing machine, the combination of an impression member, a rotary printing member, means for moving the contacting surfaces of said members at the same speed,

comprising planetary gearing constructed and adapted to vary the relative surface speeds of said members positively and automatically but uniformly throughout a complete revolution to compensate for any variation from the normal in the size of the printing member.

2. In a printing machine of the two-revolution type, the combination of an impression cylinder, a printing cylinder and means for rotating the printing cylinder a plurality of times during a single rotation of the impression cylinder and constantly at the same circumferential speed, comprising adjustable means for varying the relative speeds of said member automatically and positively to compensate throughout a complete revolution for any variation from the normal in the size of the printing cylinders.

3. In a printing machine, the combination of an impression cylinder, a printing cylinder or shell, and means connecting said cylinders for positively and uniformly varying the speed of one of them and retrieving the same during the time of impression.

4. In a printing machine, the combination of an impression cylinder, a printing cylinder, and means operated by one of said cylinders for positively rotating the other cylinder during the entire revolution thereof, and for moving it circumferentially for bringing the two cylinders into proper registration once during each revolution of the impression cylinder.

5. In a printing machine, the combination of an impression cylinder, and a printing cylinder with positive means connected with one of said cylinders for rotating the other cylinder throughout a revolution, and bringing it into proper registration therewith once during each revolution of the impression cylinder.

6. In a printing machine, the combination of an impression cylinder, and a printing cylinder of less diameter than the impression cylinder, of means operatively connected with the impression cylinder for varying the circumferential speed of the printing cylinder and for bringing said printing cylinder into proper registration with the impression cylinder once during a number of revolutions of the printing cylinder equal to the number of times the impression cylinder exceeds the printing cylinder in diameter.

7. In a printing machine, the combination with a printing couple, of adjustable means connected with one member thereof for varying the surface speed of the other member of the couple and retrieving the same during the time of impression.

8. In a printing machine, the combination with a printing couple, of adjustable means

for varying the relative circumferential speeds of the two members of the couple uniformly during a complete revolution of the printing cylinder of the couple, and for restoring them to registration during the next revolution of the printing cylinder.

9. In a printing machine, the combination with a printing couple, of adjustable means for varying the relative circumferential speeds of the two members thereof uniformly during a complete revolution of the printing cylinder of the couple, and for restoring the printing cylinder to registration with the impression cylinder during the next revolution of the printing cylinder.

10. In a printing machine, the combination with a printing couple, comprising an impression and a printing cylinder, of a cam having a part of its surface developed on a spiral and a part of its surface developed on a crank motion, and means controlled by said cam for varying the relative speed of said cylinders during the printing operation, and for varying the relative speed of said cylinders in the opposite direction during the non-printing operation of the couple, said means being controlled by the spiral part of the cam during the printing operation and by the crank motion part during the non-printing part.

11. In a printing machine, the combination with a printing couple, comprising an impression and a printing cylinder, of a cam mounted to rotate with one of said cylinders, a U-shaped lever mounted to swing on an axis and controlled by said cam, means in the center of the lever for adjusting it, and means connected with said lever for uniformly varying the speed of one of said cylinders during the printing operation, and for varying the speed of said cylinder in the opposite direction during the non-printing operation of the couple to bring said cylinders back into their original registration.

12. In a printing machine, the combination with a printing couple, comprising an impression and a printing cylinder, of a pivoted lever, means connected with one of said cylinders for swinging said lever during the rotation of said cylinders, a link adjustably connected with said lever, and means operated by said link for controlling the speed of the other cylinder.

13. In a printing machine, the combination with a printing couple, comprising an impression and a printing cylinder, of a link, means connected with one cylinder for controlling the operation of said link, and means connected with said link and controlled thereby for varying the speed of the other cylinder.

14. In a printing machine, the combination of an impression cylinder, a printing cylinder, a driving shaft, means connected

with said shaft for driving the printing cylinder comprising planetary gearing, and means connected with the impression cylinder for controlling the operation of said planetary gearing to vary the speed of the printing cylinder.

15. In a printing machine, the combination of an impression cylinder, a printing cylinder, a driving shaft, means connected with said shaft and comprising planetary gearing for driving the printing cylinder normally at the same circumferential speed at which the impression cylinder is driven, and adjustable means connected with the impression cylinder for controlling the operation of said planetary gearing to vary the speed of the printing cylinder, whereby the speed of the printing cylinder may be varied to compensate for any variation in its diameter.

16. In a printing machine, the combination of an impression cylinder, a printing cylinder, means for driving the impression cylinder comprising a gear, a gear meshing with said impression cylinder gear, a second gear mounted on the same axis as the last named gear and rotatable independently thereof, planetary gearing connecting the last two named gears, means controlled by the impression cylinder for operating said planetary gearing to vary the speed of the last named gear during its rotation, and means for connecting said last named gear with the printing cylinder.

17. In a printing machine, the combination of an impression cylinder, a printing cylinder, means for driving the impression cylinder comprising a gear, a gear meshing with said impression cylinder gear, a second gear rotatable independently of the impression cylinder gear, planetary gearing connecting said gears, means controlled by the impression cylinder for operating said planetary gearing to vary the speed of the second gear during its rotation, and means for connecting said second gear with the printing cylinder, said means comprising a universal plate adapted to transmit a uniform motion of rotation to the printing cylinder in all positions thereof.

18. In a printing machine, the combination of a printing cylinder or roll, an impression cylinder, said printing cylinder being adjustable toward and from the impression cylinder, gearing for rotating the printing cylinder comprising two rotary members substantially in axial alignment, and means for transmitting a motion of rotation through said rotary members from the first named means to the printing cylinder independently of the position of the latter.

19. In a printing machine, the combination of a cylinder, means for bodily adjusting the same laterally, rotary means for

driving said cylinder comprising two rotary members substantially in axial alinement, and a universal plate between said rotary members and directly connected with both 5 for transmitting a motion of rotation from said means to the cylinder even when said cylinder is adjusted to a position eccentric with respect to said rotary means.

20. In a printing machine, the combination of a frame, a cylinder, a bearing for said cylinder, means for adjusting said bearing on the frame and supporting it in adjusted positions, a stud supported from said frame, a gear on the stud, and a 15 rotatable plate substantially in axial alinement with said gear for transmitting a uniform motion of rotation from the gear to the cylinder.

21. In a printing machine, the combination of a frame, a cylinder, a bearing for said cylinder, means for adjusting said bearing on the frame and supporting it in adjusted positions, means for transmitting a uniform motion of rotation to the cylinder 25 comprising two rotary members substantially in axial alinement, and adjustable means for varying the speed of said cylinder during a complete revolution thereof.

22. In a printing machine, the combination of a cylinder, a bearing for said cylinder, means for adjusting said bearing and supporting it in adjusted positions, a gear and means for transmitting a uniform motion of rotation from the gear to the cylinder 35 comprising two rotary members substantially in axial alinement, said means being connected with said gear and operating to vary the speed thereof.

23. In a printing machine, the combination of a stud, a gear mounted to rotate thereon and having a hub provided with a central groove, a cylinder having a shaft substantially in axial alinement with said gear, means for adjusting said shaft trans-

versely, a head connected with the shaft and 45 provided with a groove in the face thereof, and a universal plate between the hub on the gear and the head on the shaft having projections on its opposite sides located at an angle to each other, each of said projections being adapted to enter one of said 50 grooves.

24. In a printing machine, the combination of a gear having a hub provided with a central groove, a cylinder having a shaft 55 substantially in axial alinement with said gear, means for adjusting said shaft transversely, a head on the shaft provided with a groove in the face thereof, and a universal plate between the hub on the gear and the 60 head on the shaft having projections on its opposite sides located at an angle to each other, one of said projections being adapted to enter each of said grooves whereby said cylinder may be rotated at a uniform speed 65 from said gear even when adjusted to a position eccentric with respect thereto, and means for varying the speed of said gear.

25. In a printing machine, the combination of a rotary hub, an adjustably mounted 70 printing cylinder having a shaft substantially in axial alinement with said hub, a head connected with said shaft and a universal plate between said head and hub substantially in alinement with said shaft and 75 hub, said plate having provisions on its opposite faces engaging the head and hub and located at an angle to each other, for transmitting a motion of rotation from the hub to the head.

80 In testimony whereof I have hereunto set my hand, in the presence of two subscribing witnesses.

ROBERT T. JOHNSTON.
